(57) CLAIM

The ornamental design for a heated camping chair, as shown and described.

DESCRIPTION

FIG. 1 is a perspective view of a heated camping chair showing the new design;

FIG. 2 is another perspective view thereof;

FIG. 3 is a front elevation view thereof;

FIG. 4 is a rear elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is an enlarged view of the encircled portion in FIG. 5; and,

FIG. 10 is an enlarged view of the encircled portion in FIG. 6.

The equal length broken lines depict portions of the heated camping chair that form no part of the claimed design.

The long dash-short dash lines in FIGS. 5, 6, 9, and 10 illustrate the enlarged view indicators and form no part of the claimed design.

1 Claim, 10 Drawing Sheets
